UNITED STATES PATENT OFFICE.

NICHOLAS C. BOHR, OF SYRACUSE, NEW YORK.

DESIGN FOR A SHOE.

SPECIFICATION forming part of Design No. 31,914, dated November 28, 1899.

Application filed October 28, 1899. Serial No. 735,134. Term of patent 7 years.

To all whom it may concern:

Be it known that I, NICHOLAS C. BOHR, a citizen of the United States, residing at Syracuse, in the county of Onondaga, in the State 5 of New York, have invented a new and original Design for Shoes, of which the following is a specification, reference being had to the accompanying drawing, forming a part thereof.

The figure is a perspective view of a shoe, showing my new design.

As shown in the drawing, the leading or material feature of my design consists in the outwardly-extending edge of the sole 1, which is provided with two rows of ribs or stitches 5 peculiarly formed and arranged, extending around the front portion of the shoe. The stitches or ribs of the inner row 2 next the upper 3 are arranged zigzag or diagonally, as hereshown, forming a continuous series. The

outer row 4 forms a band parallel to the inner; but its stitches or ribs are arranged continuously in substantially a line following the outer edge of the sole.

This design is adapted to be applied to various kinds of boots, shoes, and slippers, particularly to men's heavier boots and shoes.

Having described my invention, what I claim as new, and desire to protect by Letters Patent, is—

The design for a shoe, as herein shown and described.

In testimony whereof I have hereunto signed my name.

NICHOLAS C. BOHR. [L. S.]
